UNITED STATES PATENT OFFICE.

WILLIAM C. CURRAN, OF CINCINNATI, OHIO.

OPENER.

1,138,456.

Specification of Letters Patent.

Patented May 4, 1915.

Application filed May 2, 1913. Serial No. 765,107.

To all whom it may concern:

Be it known that I, WILLIAM C. CURRAN, a citizen of the United States, residing at Cincinnati, in the county of Hamilton and State 5 of Ohio, have invented a new and useful Opener; and I do hereby declare the following to be a full, clear, and exact description of the invention, such as will enable others skilled in the art to which it appertains to 10 make and use the same.

This invention relates to a new and useful combination implement.

As an object of the invention, it is the aim to provide an article, such as a key, which 15 is in common use embodied with a plurality of devices, such as a button-hook, an opener for a mineral water bottle, a file for mani- 20 curing or a match striker and a screw driver including a small tack extracting claw.

Another object of the invention is the convenience and readiness with which the devices may be carried by a key blank.

The invention comprises further features 25 and combination of parts, as hereinafter set forth, shown in the drawings and claimed.

In the drawings:—Figure 1 is a view in perspective of the key blank, showing the same provided with a plurality of devices 30 as narrated above. Fig. 2 is an edge view showing the mineral bottle opener in position to extract the cork. Fig. 3 is a sectional view on line 3—3 of Fig. 1, showing clearly how the mineral bottle openers are 35 constructed and forming a part of the key handle. Fig. 4 is a view showing the implement used another way for extracting a cork. Fig. 5 is a detail view showing another form of cork being extracted. Fig. 6 40 shows a bottle cap as being lifted. Fig. 7 is a view showing the opening tool used for extracting a staple or the like adjacent the edge of a board or a similar support.

Referring more particularly to the drawings, 1 designates a key blank, which may be filed to construct a key. This blank 1 forms an integral part of the key shank 2, one end of which terminates in flat sides 3, which taper or merge together at the extreme end 4 of the shank to form a screw engaging means 5, provided with a notch 6, adapted for use in extracting small tacks

and the like. The other end of the shank terminates in a handle 7, substantially of the usual construction, with the exception 55 that the metal intermediate the usual opening 8 of the handle is constructed to form mineral bottle openers 9, which extend outwardly from opposite sides of the handle for a portion of their length, and then in opposite directions and parallel with each other and with the handle, in such wise as to enable one or the other to be embedded in the cork, when by allowing the shank to engage the edge of the bottle about the opening 65 thereof as a fulcrum, the cork may be extracted, as shown in Fig. 2. The reverse of this action may be enacted, for instance, one of the prongs or bottle openers may be embedded in the cork, and the handle allowed 70 to engage the periphery of the bottle opening, in order to extract the cork, as shown in Fig. 4. Projecting from one edge of the handle is a button-hook 12, while on the shank intermediate the key blank and the 75 handle a roughened surface 14, such as a file or the like is provided, which not only may be used in maniuring, but as means upon which a match may be struck.

In Fig. 7 the tool is designed to be used 80 as a staple extractor for extracting a staple or the like adjacent the edge of a board or other support. For instance, the tool may be arranged so that one of the prongs 9 may be used for first starting the extraction of a 85 staple, sufficiently to permit the staple to enter through the opening of the enlargement and loop over the opposite prongs. Then by fulcrumming the handle on the edge of a board the staple will be easily extracted. 90

From the foregoing it is apparent that there has been devised an improved, simple and efficient combination implement, and one which has been found desirable and practical, owing to the convenience and 95 readiness of the very necessary articles or devices.

The invention having been set forth, what is claimed as new and useful is:—

An opening tool comprising a handle hav- 100 ing an enlargement provided with an elongated transversely disposed opening, said enlargement upon directly opposite sides having tapering prongs extending from and

2
offset from opposite sides of the enlargement and protruding in opposite directions, said prongs being disposed in parallelism with one another and said handle, and in conjunction with the handle constituting an opener.

In testimony whereof I have signed my

name to this specification in the presence of two subscribing witnesses.

WILLIAM C. CURRAN.
